UNITED STATES PATENT OFFICE.

AUGUST L. WARCKMEISTER, OF NEWARK, NEW JERSEY, ASSIGNOR TO
CHARLES A. WHARTON, OF SAME PLACE.

ROLLS OF HAT-FELTING MACHINES.

SPECIFICATION forming part of Letters Patent No. 243,179, dated June 21, 1881.

Application filed April 30, 1881. (No model.)

To all whom it may concern:

Be it known that I, A. L. WARCKMEISTER, a subject of the Emperor of Germany, residing in the city of Newark, county of Essex and State of New Jersey, have invented 5 certain new and useful Improvements in Hat-Felting Rolls, fully described and represented in the following specification and the accompanying drawings, forming a part of the same.

10 My invention relates to an improvement in the rolls of hat-felting machines; and it consists in mounting smaller rollers in or upon the surface of such rolls in lieu of the ribs hitherto employed to indent the bundle of felts rotated 15 by the rolls.

In the present practice, in hat-sizing machines, several hat-felts are made into a round bundle and laid into the cavity between two adjacent rolls, which rotate in the same direction, as indicated in Fig. 1 of the drawings annexed, and are there rolled and indented by ribs formed upon the surface of the rolls. This operation is intended to imitate the hand 20 rolling and working, by which hats are felted most successfully; but the positive rotary motion of the surface of a solid roll and its projecting ribs causes a greater degree of friction 25 and rubbing than is desirable, which it is the chief purpose of my invention to reduce. The 30 means I have devised to accomplish this object are shown in the annexed drawings, of which—

Figure 1 is an end view of the rolls detached from a three-roll machine. Fig. 2 is a side 35 view of the top roll; Fig. 3, a side view of the front roll, and Fig. 4 a side view of the rear roll.

A is the top roll; B, the front roll, and C the rear roll; and to illustrate the different modes 40 of carrying out my invention I have shown the smaller rollers applied to each of the three main rolls in a different manner.

At A is shown a common ribbed roll having smaller rollers *r r*, mounted between the ribs 45 *a*, with the surfaces of the small rollers projecting above the ribs.

At B is shown a roll having eight small rollers, *r r r*, secured in gutters formed in the main roll for the greater part of its length, their 50 convex surfaces protruding somewhat above the cylindrical body of the main roll.

At C is shown a roll provided with two sets of smaller rollers, arranged in grooves or gutters extending from about the middle of the roll's length to its ends. The rollers in each 55 set are disposed, alternately, upon the body of the main roll, with the rollers of the other set, their projecting surfaces thus striking, alternately, against the felt at its right and left hand side. The rollers are provided with bearings *b* and journals *c*, the latter being secured to the body of the roll by screws, as shown upon roll A, or by a shank or pin driven into the roll, as upon roll B.

The arrows *d* indicate the motion of the three 60 rolls, and the felts formed in a bundle between the rolls are lettered *f*. Arrows *e e* also indicate the rotary motion of the small rollers when in contact with the felts, and it is easy to perceive that their rotation diminishes the 65 friction of the felts against the main roll without reducing at all the indurating effect for which ribs are commonly employed. The projections formed upon the main roll by the revolving rollers *r r* thus operate very nearly 70 like the knuckles and ball of the hand, as commonly used by an operator in working over a roll of felts.

I have found that the felting done by my improved rolls was more rapid and thorough 75 than that done by any kind of ribbed roll in use, and having shown how the smaller rollers may be disposed upon the larger rolls and secured thereto in any desired manner, I do not limit myself to any particular way of mounting 80 them upon such rolls.

I am aware that aprons have been made of a series of rollers moving in contact with bundles of felts, and that fixed rollers have been mounted around a revolving drum as in patent to E. Beesley; but the slow rate of motion possible with all such devices has caused them to be superseded very generally by rapidly-revolving rolls operated in pairs or sets, between which the felts could be inserted and removed with facility; and it is to such quickly-running rolls mounted in pairs or in sets, with or without top-pressing rolls, that my auxiliary rolls *r* are applicable.

Although the main rolls shown in the drawings are of uniform diameter from end to end, 90 it is obvious that my improvement could be

applied with equal facility to rolls made smaller in the middle or at the ends; and I do not, therefore, limit myself to the combination of the smaller rollers with the parallel rolls shown in the drawings.

5 The rollers *rr* may also be made conical in shape or larger at the ends or at the middle, as desired, to produce the most effective pressure upon the felts, and by means of the latter shape applied to rollers arranged, as shown in Fig. 4, the convex shape of the felt bundle may be largely compensated, and its substance pressed quite uniformly by the small rollers *rr*.

10 I therefore claim my invention as follows:

15 1. A roll for hat-felting machines of the class herein described, provided with a series of small rollers projecting beyond the general surface of the main roll, substantially as herein set forth.

2. The combination of a ribbed roll with 20 small rollers mounted between the ribs and projecting beyond them, as herein shown and described.

3. In combination with a cylindrical roll provided with grooves to receive small rollers, 25 a series of such rollers secured at each end of the main roll and extending to the middle of the main roll, for the purpose shown and described.

10 In testimony whereof I have hereunto set 30 my hand in the presence of two subscribing witnesses.

AUG. L. WARCKMEISTER.
